PORTABLE POWER DRILL ATTACHMENT

Donald George Salfer, Wabasso, Minn.

Application November 9, 1956, Serial No. 621,374

4 Claims. (Cl. 77—14)

The present invention relates to an attachment for a portable power drill for supporting and feeding the drill into a work piece.

An object of the present invention is to provide an attachment for a portable power drill which lends itself to ready attachment to a work piece for feeding the drill into the work piece, one which is readily and easily mounted upon the steadyng handle of the drill and serves as a steadyng handle of the drill when attached, as well as one which is sturdily constructed and of simple structure, economical to manufacture and assemble, and one which is highly effective in action.

These and other objects and advantages of the present invention will become fully apparent when taken in connection with the annexed drawings, in which:

Figure 1 is an elevational view of a part of a power drill with the attachment of the present invention installed thereon, showing the drill in operation drilling a work piece, the arrow illustrating the direction of movement of the handle of the attachment for feeding the drill into the work piece;

Figure 2 is a plan view of the assembly of Figure 1;

Figure 3 is an end view of the assembly of Figure 1;

Figure 4 is a sectional view, on an enlarged scale, taken on the line 4—4 of Figure 3; and

Figure 5 is a sectional view, on an enlarged scale, taken on the line 5—5 of Figure 3.

Referring in greater detail to the drawings in which like numerals indicate like parts throughout the several views, the attachment of the present invention is for use with a portable power drill, indicated by the reference numeral 10, and having a steadyng handle 11 projecting perpendicularly from the housing of the drill 10. The attachment comprises an outer sleeve 12 and an inner sleeve 12' circumsposed about the steadyng handle 11 so that one end of the sleeve 12 is adjacent the inner end of the steadyng handle 11 and the other end of the sleeve is inwardly of and adjacent the outer end of the steadyng handle 11.

A lever 13, disposed horizontally, is arranged longitudinally of the sleeve 12 and on one side thereof and has a portion adjacent one end extending beyond the sleeve and which is adjacent the inner end of the steadyng handle 11 and has the portion adjacent the other end extending beyond the other end of the sleeve 12, the latter sleeve ending adjacent the outer end of the steadyng handle 11. On the other side of the sleeve 12 another lever 14 is similarly positioned and is arranged in parallel spaced relation with respect to the lever 13.

Means is provided connecting the portions of the levers 13 and 14 adjacent the inner end of the steadyng handle 11 to a sleeve 12 for upward and downward movement about horizontal axes. Specifically, this means embodies a pair of diverging arms having their converging ends fixedly secured to the sleeve 12, the arms being indicated by the reference numerals 15 and 16, portions of the arms 15 and 16 adjacent to and inwardly of their diverging ends being longitudinally of the adjacent portions of the levers

2

13 and 14. The diverged ends of the arms 15 and 16 are pivotally connected to the levers 13 and 14, respectively, inwardly of their ends which project beyond the inner end of the steadyng handle 11 for upward and downward movement of the levers 13 and 14 about their pivot points as an axis.

In Figure 4, it will be seen that the lever 13 is pivotally connected to the arm 15 by means of a bolt 17, there being provided a frictionless bearing bushing 18 serving as a mounting for the bolt 17 and having a flange 19 interposed between the adjacent portions of the lever 13 and the arm 15. The lever 14 is similarly connected to the arm 16.

Means embodying a handle 21 connects the other ends of the levers 13 and 14 together, the handle 21 being movable downwardly, as indicated by the arrow in Figure 1, for moving the levers 13 and 14 together downwardly.

Means is provided on the ends of the levers 13 and 14 adjacent their points of connections to the arms 15 and 16 for engaging a work piece 22 for moving the drill 10 toward the work piece 22 upon execution of movement of the handle 21 downwardly. Specifically, this means comprises a loop of chain 23 having one end fixed to one end of the lever 13 and the other end fixed to the end of the lever 14.

Spring means is provided for urging the levers 13 and 14 to their upward movement position and, specifically, this means consists in a pair of springs 24 and 25, the spring 24 having one end fixed to the lever 13 and the other end fixed to the sleeve 12, and the spring 25 having one end fixed to the lever 14 and its other end fixed to the sleeve 12.

Set screws 27 and 31 are provided and are threaded into tapped holes in the ends of the sleeve 12'.

35 In operation, the attachment of the present invention is quickly installed upon the steadyng handle by slipping the sleeve 12' thereover. The sleeve 12 is then slipped over the inner sleeve 12' and the set screws 27 and 31 are inserted in the holes in the sleeve 12' and drawn up snug. The chain 23 is rapidly looped under a work piece 22 and with the motor of the drill 10 turning the bit 28, pressure downwardly upon the handle 21 will serve to steady the drill 10 and also feed the bit 28 through the work piece 22.

40 The drill 10 is of conventional manufacture having a pistol grip handle 29 and a breast-rest handle 31.

What is claimed is:

1. An attachment for a portable power drill having a steadyng handle having an inner end and an outer end comprising a sleeve circumsposed about said steadyng handle so that one end thereof is adjacent the inner end of said steadyng handle and the other end is adjacent the outer end of said steadyng handle, a lever arranged longitudinally of and on each side of said sleeve and having the portion adjacent one end beyond said sleeve one end and having the portion adjacent the other end beyond said other sleeve end, means connecting the portions adjacent said one end of said levers to said sleeve for up and down movement about horizontal axes, means connecting the other ends of said levers for movement together, and means carried by said one ends of said levers adapted to engage a work piece and operable to feed said drill into said work piece upon execution of downward movement of said levers.

55 2. An attachment for a portable power drill having a steadyng handle having an inner end and an outer end comprising a sleeve circumsposed about said steadyng handle so that one end thereof is adjacent the inner end of said steadyng handle and the other end is adjacent the outer end of said steadyng handle, a lever arranged longitudinally of and on each side of said sleeve and having the portion adjacent one end beyond said sleeve end

and having the portion adjacent the other end beyond said other sleeve end, means connecting the portions adjacent said one end of said levers to said sleeve for up and down movement about horizontal axes, means connecting the other ends of said levers for movement together, means carried by said one ends of said levers adapted to engage a work piece and operable to feed said drill into said work piece upon execution of downward movement of said levers, and spring means operatively connecting said levers to said sleeve for urging said levers toward upward movement position.

3. An attachment for a portable power drill having a steadyng handle having an inner end and an outer end comprising a sleeve circumsposed about said steadyng handle so that one end thereof is adjacent the inner end of said steadyng handle and the other end is adjacent the outer end of said steadyng handle, a lever arranged longitudinally of and on each side of said sleeve and having the portion adjacent one end beyond said sleeve one end and having the portion adjacent the other end beyond said other sleeve end, means embodying a pair of diverging arms each having its diverging end connected to the portion of the adjacent lever adjacent said one end thereof for up and down movement of said lever about a horizontal axis and having its converging end fixedly secured to said sleeve inwardly of said one end of the latter, means connecting the other ends of said levers for movement together, means carried by said one ends of said levers adapted to engage a work piece and operable to feed said drill into said work piece upon execution of downward movement of said levers.

4. An attachment for a portable power drill having a steadyng handle having an inner end and an outer end comprising a sleeve circumsposed about said steadyng handle so that one end thereof is adjacent the inner end of said steadyng handle and the other end is adjacent the outer end of said steadyng handle, a lever arranged longitudinally of and on each side of said sleeve and having the portion adjacent one end beyond said sleeve one end and having the portion adjacent the other end beyond said other sleeve end, means embodying a pair of diverging arms each having its diverging end connected to the portion of the adjacent lever adjacent said one end thereof for up and down movement of said lever about a horizontal axis, and having its converging end fixedly secured to said sleeve inwardly of said one end of the latter, means embodying a handle connecting the other ends of said levers for movement together, means embodying a loop of flexible chain carried by said one ends of said levers adapted to engage a work piece and operable to feed said drill into said work piece upon execution of downward movement of said levers, and spring means operatively connecting said levers to said sleeve for urging said levers toward their upward movement position.
